(57) **CLAIM**

The ornamental design for a light transmitting optic for a lighting device, as shown and described.

DESCRIPTION

FIG. 1 is a front facing perspective view of the ornamental design for the light transmitting optic for a lighting device; FIG. 2 is a front view of the ornamental design for the light transmitting optic for a lighting device;

FIG. 3 is a rear view of the ornamental design for the light transmitting optic for a lighting device;

FIG. 4 is a right side view of the ornamental design for the light transmitting optic for a lighting device;

FIG. 5 is a left side view of the ornamental design for the light transmitting optic for a lighting device;

FIG. 6 is a top view of the ornamental design for the light transmitting optic for a lighting device; and,

FIG. 7 is a bottom view of the ornamental design for the light transmitting optic for a lighting device.

The light transmitting optic for a lighting device is shown having a break and any portion of the design not shown in the drawings forms no part of the claimed design.

1 Claim, 5 Drawing Sheets
